UNITED STATES PATENT OFFICE.

CHARLES A. BURT, OF DES MOINES, IOWA.

ADJUSTABLE HAT-GROMET.

1,185,979.

Specification of Letters Patent.

Patented June 6, 1916.

Application filed March 23, 1915. Serial No. 16,499.

To all whom it may concern:

Be it known that I, CHARLES A. BURT, a citizen of the United States, residing at Des Moines, in the State of Iowa, have invented certain new and useful Improvements in Adjustable Hat-Gromets; and I do hereby declare the following to be a full, clear, and exact description of the invention, such as will enable others skilled in the art 10 to which it appertains to make and use the same.

The present invention relates to a hat-stiffening band of adjustable length, such as is used for instance to give form to the extended circular or quasi-circular crown of a sailor's hat. In this latter connection a band of this kind is known as a gromet.

The object of the invention is to provide such a hat band as can be instantly altered 20 as to its length, making it thereby adjustable to hats of different sizes. In sailors' hats this device is also useful to accommodate the gromet to changes in size of the hat, due to shrinkage from wetting or other 25 causes.

The invention is shown in certain preferred forms in the accompanying drawings wherein—

Figure 1 is a side view of a sailor's hat 30 with the gromet inserted, Fig. 2 is a perspective view of the adjusting clip in place, Fig. 3 is a longitudinal section of the clip, Fig. 4 is a transverse section thereof on the line 4—4 in Fig. 3, and Fig. 5 is an elevation of a modified form of clip.

A sailor's hat of conventional pattern usually has a rim 10, and a soft or flexible crown 11, which is given shape by an internal gromet shown in dotted lines in Fig. 40 1. The ends of this band 12 are made to overlap, as in Figs. 2 and 3, and in my improvement the overlapping portions are passed through a clip, comprising a base 13 having turned up edges 14 between which 45 are pivotally mounted two jaws 15. The outer tips of these jaws are firmly held down against the band 12 by a spring. In the form shown this spring takes the form

of one or more pieces of hard spring wire 16, preferably coiled around the pivots on 50 which the jaws turn, and having its or their outer ends soldered to the jaws. These wires are so arranged as to tend constantly to press the outer tips of the jaws toward the band 11. By simply pressing upon the 55 inner ends of the jaws, the spring pressure can be relieved to permit the band to be given a new position, in which it is held by the jaws when the thumb pressure is released. The inner ends of the jaws, as 60 shown in Figs. 2 and 3, are curved inwardly and are somewhat widely separated. As shown in Fig. 5, these ends may lie substantially in the same plane and be brought together, so as almost to touch. Indeed, 65 various forms can be given to the various parts of the gromet without departing from my invention.

What I claim is—

1. An expansible hat gromet, comprising 70 a resilient strip having its ends overlapping to form an adjustable band, a base mounted over the overlapping ends of said band and provided with inwardly projecting flanges, and relatively spaced spring-impressed 75 gripping jaws pivoted to said flanges and normally adapted to clamp the overlapping ends of said strip together, substantially as described.

2. An expansible hat gromet, comprising 80 a resilient strip having its ends overlapping to form an adjustable band, a base mounted over the overlapping ends of said band and provided with inwardly projecting flanges, oppositely disposed relatively spaced gripping jaws pivoted to said flanges, and a wire 85 spring connected to the pivots of said jaws and having its free ends engaging said jaws and normally pressing same into the gripping position, substantially as described. 90

In testimony whereof, I affix my signature, in presence of two witnesses.

CHARLES A. BURT.
